UNITED STATES PATENT OFFICE.

GEORGE W. LAWHON AND WILLIAM LAWHON, OF KNOXVILLE, TENNESSEE.

CISTERNS CUT-OFF.

SPECIFICATION forming part of Letters Patent No. 330,410, dated November 17, 1885.

Application filed September 18, 1885. Serial No. 177,461. (No model.)

To all whom it may concern:

Be it known that we, GEORGE W. LAWHON and WILLIAM LAWHON, citizens of the United States, residing at Knoxville, in the county of Knox and State of Tennessee, have invented a new and useful Improvement in Cistern Cut-Offs, of which the following is a specification, reference being had to the accompanying drawings.

10 Our invention relates to an improvement in cistern cut-offs; and it consists in the peculiar construction and combination of devices, that will be more fully set forth hereinafter, and particularly pointed out in the claim.

15 In the drawings, Figure 1 is a perspective view of a cistern cut-off embodying our invention, partly broken away to disclose the interior arrangement. Fig. 2 is a vertical sectional view of the same.

20 A represents a vertical pipe that leads from the eaves-troughs of a house and communicates at its lower end with a discharge-pipe, B, for the impure water that runs from the roof at the beginning of a rain, and with a 25 pipe, C, that leads to a cistern to supply the latter with pure rain-water.

D represents a hollow rock-shaft journaled transversely below the pipe A, and between the upper ends of the pipes B and C.

30 E represents a cut-off valve that is concave on its upper side and has its ends rounded, as shown. This valve is secured transversely on the rock-shaft, the latter being located at the center thereof, and the valve is provided 35 with a central bottom opening, e, that communicates with the hollow rock-shaft. An arm, F, is secured to one of the projecting ends of the rock-shaft, at right angles to said shaft, and a weight, G, is attached to the outer

40 end of the arm to normally tilt the valve and cause the latter to cut off the pipe C and connect the pipe A with the dirty-water pipe B. A hollow arm, H, is attached to and communicates with the hollow rock-shaft, and extends therefrom in a substantially opposite direction from the arm F, at an angle of about one hundred and thirty-five degrees therefrom. The arm H is somewhat longer than the arm F, and at its outer end is secured 45 to a water-chamber, I, with which the arm H communicates. This chamber is provided at

a suitable point with openings i, through which the water in the chamber may leak out slowly. At the beginning of a rain the water from the roof is fouled with dust and dirt on the roof, and this impure water is directed by the valve out through the pipe B. A portion of the water passes through the opening in the bottom of the valve into the hollow rock-shaft, and from thence finds its way 60 through the hollow arm H into the water-chamber, in which it slowly accumulates until the weight of said chamber overbalances the weighted arm F, when the valve is tilted to the position shown in dotted lines in Fig. 2, 65 thus cutting off the pipe B and directing the water from the pipe A into the pipe C to the cistern. The openings i permit the water to leak slowly from the water-chamber, but not so fast as it is supplied during the rain. 70 When the rain is over, the water in the water-chamber leaks out until the weighted arm overbalances it, when the valve is tilted to its initial position, ready to direct the first dirty water of the next rain away from the cistern, 75 as before.

Having thus described our invention, we claim—

The combination of the pipe A and the discharge-pipe and cistern-supply pipe communicating therewith, the hollow rock-shaft, the cut-off valve secured to said shaft, and having the central bottom opening communicating therewith, the weighted arm F, attached to the rock-shaft, to tilt the valve and cause it to cut 85 off the supply-pipe normally, and the hollow arm H, connected to the hollow rock-shaft, and the water-chamber I on the arm H and having the leak-openings i, substantially as described.

In testimony that we claim the foregoing as our own we have hereto affixed our signatures in presence of two witnesses.
